UNITED STATES PATENT OFFICE.

FRANK LO CASTRO, OF BROOKLYN, NEW YORK, ASSIGNOR TO ABRAHAM LEVY, DOING BUSINESS AS UNITED METAL GOODS MFG. CO.

DESIGN FOR A CLOCK CASE.

Application filed January 19, 1929. Serial No. 29,677. Term of patent 3½ years.

To all whom it may concern:

Be it known that I, FRANK LO CASTRO, a citizen of Italy, residing at Brooklyn, in the county of Kings and State of New York, have invented a new, original, and ornamental Design for Clock Case, of which the following is a specification, reference being had to the accompanying drawing, forming part thereof.

The figure is a front elevational view of a clock case, showing my new design.

I claim:

The ornamental design for a clock case as shown.

FRANK LO CASTRO.
